UNITED STATES PATENT OFFICE.

MARK W. DEWEY, OF SYRACUSE, NEW YORK, ASSIGNOR OF TWO-THIRDS
TO EMIL LAASS AND CHARLES H. DUELL, OF SAME PLACE.

TELEGRAPHIC-PRINTING CODE.

SPECIFICATION forming part of Letters Patent No. 394,961, dated December 25, 1883.

Application filed March 14, 1883. Serial No. 267,171. (No model.)

To all whom it may concern:

Be it known that I, MARK W. DEWEY, of Syracuse, in the county of Onondaga, in the State of New York, have invented new and useful Improvements in Telegraphic-Printing Codes, of which the following, taken in connection with the accompanying drawing, is a full, clear, and exact description.

This invention consists in a new telegraphic-printing code especially adapted for the transmission of messages by the combination of duplex or quadruplex lines, transmitting-keys arranged to be operated two or more simultaneously at one end of said lines, and a corresponding number of markers at the opposite end of the lines arranged at right angles to the line of travel of the paper and operated respectively by the aforesaid transmitting-keys, as described in my prior application for patent, Serial No. 255,695, filed November 21, 1887.

The annexed drawing presents a ribbon of paper with my improved telegraphic-printing code imprinted thereon.

It will be observed that said code consists, first, in the employment of marks of different lengths; secondly, in disposing in a row at right angles to the line of travel of the paper the plurality of marks designating a single letter or character; thirdly, in making the

marks in each row of corresponding lengths; and, fourthly, distinguishing the different letters or characters from each other, either by the difference in the lengths of the marks or by the distances of the marks from the longitudinal edges of the paper, as shown in the drawing hereto annexed.

What I claim is—

The within-described telegraphic-printing code, consisting, first, in marks of different lengths; secondly, in the arrangement in a row at right angles to the line of travel of the paper of the plurality of marks designating a single letter or character; thirdly, in making the marks in each row of corresponding lengths, and, fourthly, distinguishing the different letters or characters from each other, either by the difference in the lengths of the marks or by the distances of the marks from the longitudinal edges of the paper, substantially as described and shown.

In testimony whereof I have hereunto signed my name, in the presence of two witnesses, at Syracuse, in the county of Onondaga, in the State of New York, this 12th day of March, 1888.

MARK W. DEWEY. [L. S.]
